UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

HEAT-TREATING APPARATUS FOR PACKAGED GOODS.

Original application filed June 7, 1921, Serial No. 475,643. Divided and this application filed May 16, 1922. Serial No. 639,438.

To all whom it may concern:

Be it known that I, ALBERT R. THOMPSON, a citizen of the United States, residing at San Jose, in the county of Santa Clara and 5 State of California, have invented certain new and useful Improvements in Heat-Treating Apparatus for Packaged Goods, of which the following is a specification.

This application is a division of my pending application, Serial Number 475,643, filed June 7, 1921, for a patent for method of processing milk.

My invention relates to apparatus for heat-treating packaged goods, and while 10 specially adapted for use in the processing of milk according to the method described in the application above identified, is also adapted for the treatment of other comestibles, particularly as a cooker in the 15 canning art, in which it is necessary to subject the goods according to their nature, to the cooking heat during varying time periods.

The variable time period in cookers of this 20 type is commonly effected in one of two ways, namely, either by varying the speed of the carrier which advances the goods through the treating chamber, or by varying the length of the path pursued by the goods. Cookers are also known, especially of the 25 pressure type, in which the goods are carried through successive compartments, in which the temperature varies one from the other. In such machines it is obvious that if the temperature in one compartment be 30 so reduced as to fail of cooking function the time of cook would be proportionately varied. It is to this idea in addition to its function as a step in the method of processing milk disclosed in my former application of which this is a division, that my invention is directed, and to the end that it 35 may be conveniently and effectively embodied in a practical device my invention 40 consists in the novel apparatus for heat-treating packaged goods which I shall hereinafter fully describe by reference to the accompanying drawings, in which the figure 45 is a longitudinal vertical section of my apparatus.

In the following description, I shall, for the sake of simplicity refer to the packaged goods as cans.

A is a shell provided with a can inlet 1

and a can outlet 2. Within the shell, around 55 its inner circumference is a fixed, helically directed rail 3 which forms one member of a can track. The other member is a rotatable reel 4, carrying a peripheral series of spaced rails 5 parallel with the reel axis and 60 lying in such proximity to the fixed, helically directed rail as to form therewith a support for the cans, said rails 3 and 5 coacting to produce a helical path through which a procession or stream of cans is continuously advanced from the inlet 1 to the outlet 2, in a manner common to and well known in the art. The reel 4 has a shaft 4' for rotating it, the shaft being driven by a gear 4'' or other suitable means.

Upon the shaft 4' and rotating with it are the spaced cross-plates 6 lying between the end heads of the reel. These plates may be in any suitable number, two being here shown, dividing the shell into three successive compartments. Said plates are imperforate, but as will be seen the several compartments peripherally communicate through the continuous can-track formed by the rails 3 and 5, but as this track is, in operation, filled with cans, the communication is but slight, and this, taken in connection with the imperforate cross plates 6 renders it possible, in practise, to give to and maintain in each compartment a different temperature 65 degree without appreciable interchange. The heating medium is preferably water, indicated by 7. This is supplied by a pipe 8, and is drained off when necessary through a bottom chamber 9 and a drain 10. The 70 water is heated by steam admitted through perforated pipes. For example, one steam pipe 11 enters and is housed in the underlying drain chamber 9 and lies below the first compartment. Another steam pipe 12 lies 75 in the chamber 9 below the third compartment, and still another steam pipe 13, conveniently passing through the steam pipe 12, lies in the chamber 9 below the second compartment. Each of these pipes is independently controlled as to the volume of steam admitted, in accordance with the temperature desired in each compartment. For this purpose I have shown the cocks 14, 15 and 16 80 respectively. Thus a different temperature may be maintained in each compartment of the shell A, or the steam may be cut off from one or more compartments as desired.

In order to further guard against appreciable interchange of heat between the compartments, there are division plates 17 depending from the bottom of the shell into the chamber 9.

The function of this apparatus, in processing milk contained in hermetically sealed cans is that of a pre-heater. For example the cans are subjected in the first compartment to a temperature of about 70° F.; in the second compartment, to a temperature of about 120° F.; and in the third compartment to a temperature of about 180° F.

In using the apparatus as a variable time cooker, the operation is as follows:—

If the goods are of a nature to require the longest time of cook, all the compartments are given a cooking temperature, and the cans are passed through the whole length of the shell from inlet to outlet during which they are subjected for the full time of their travel to said temperature.

But if the goods require a shorter time of cook, the temperature of the first compartment is either reduced below that required for cooking or the steam to said compartment is cut off completely, while the temperature of the second and third compartments is maintained at the degree required for cooking. Therefore, though the cans enter at the inlet 2 and pass through the first compartment, they are not exposed to a cooking temperature therein but they are so exposed in the succeeding compartments, and the time of cook is thus shortened. Likewise the very shortest cook may be had by cutting off the steam from the first and second compartments and permitting the cooking in the third compartment only.

It should be noted that the cross-plates 6 separating the compartments are part of and rotate with the reel 4. They do not, therefore, present any obstruction to the continuity of the can path, as non-rotating or fixed partitions would, which latter would throughout but when filled with cans, the interchange of heat is negligible.

I claim:—

1. An apparatus for heat treating packaged goods comprising a heating shell having an inlet and an outlet; a helically di-

rected fixed rail within the shell about the inner surface of its periphery; a rotatable reel within the shell having a peripheral series of rails parallel with the reel axis and coacting with the helically directed rail to form a path for conducting the goods through the shell from the inlet to the outlet; an imperforate cross plate carried by and within the reel and rotating therewith, said plate dividing the reel into successive compartments communicating through the goods path; and means for maintaining different temperatures in each compartment.

2. An apparatus for heat treating packaged goods comprising a heating shell having an inlet and an outlet; a helically directed fixed rail within the shell about the inner surface of its periphery; a rotatable reel within the shell having a peripheral series of rails parallel with the reel axis and coacting with the helically directed rail to form a path for conducting the goods through the shell from the inlet to the outlet; an imperforate cross plate carried by and within the reel and rotating therewith, said plate dividing the reel into successive compartments communicating through the goods path; and means for maintaining different temperatures in each compartment, 75 consisting of separately controllable steam pipes.

3. An apparatus for heat-treating packaged goods comprising a heating shell having an inlet and an outlet; a helically directed fixed rail within the shell about the inner surface of its periphery; a rotatable reel within the shell having a peripheral series of rails parallel with the reel axis and coacting with the helically directed rail to form a path for conducting the goods through the shell from the inlet to the outlet; an imperforate cross plate carried by and within the reel and rotating therewith, said plate dividing the reel into successive compartments communicating through the goods path; a drain chamber underlying the shell and communicating with the shell and separately controllable steam pipes housed within said drain chamber and adapted to supply steam to said compartments respectively.

In testimony whereof I have signed my name to this specification.

ALBERT R. THOMPSON.
